RUBBER GOLF TEE WITH HOLLOW BASE

Paul J. Barnard, Rockford, Ill.

Application January 2, 1951, Serial No. 203,981

2 Claims. (CL. 273—33)

1

This invention relates to golf tees made of yieldable material such as rubber and having a hollow base adapted to support a golf ball while resting directly on the ground surface.

The general object of the invention is to provide a tee of the above character which is of simple and rugged construction, which permits of proper contact under all conditions between a ball supported thereon and a golf club face, and which enables a golf ball to be supported at a substantially uniform height from an uneven or grass-covered ground surface.

The invention also resides in the novel construction of one side of the base and the bottom thereof to achieve the foregoing objects.

Other objects and advantages of the invention will become apparent from the following detailed description taken in connection with the accompanying drawings, in which

Figure 1 is a perspective view of the improved tee.

Fig. 2 is an end elevational view.

Fig. 3 is a fragmentary bottom view.

Figs. 4 and 5 are sectional views taken respectively along the lines 4—4 and 5—5 of Fig. 3.

As shown in the drawings for purposes of illustration, the improved tee comprises generally a post 10 upstanding from an enlarged base 11 which is connected at its periphery with one end of a flexible element or band 12, the other end of which is attached to a weighted disk 13 around which the tee proper swings as a golf ball 14 is driven from a cup 15 in which the ball is supported on the upper end of the post 10. Preferably, all of these parts are formed in a single integral piece by molding from relatively live and readily flexible rubber or equivalent plastic material. In order to minimize the size of the weighted disk, a piece of metal may be molded therein.

The major portion of the periphery of the base 11 is an arc 16 concentric with the axis of the post 10 and extending more than a half revolution around the latter past the end of the band 12 and to points 17 substantially aligned with one edge of the band. The radius of the arc 16 is approximately equal to or slightly larger than that of an ordinary golf ball. The remainder of the base periphery is a chord 18 spaced from the axis a distance substantially less than the radius of the ball 14 so as to be disposed out of contact with the face of a golf club head as the latter strikes the ball in its sweep close to the ground surface.

The top surface of the base 11 slopes upwardly

2

quite sharply from the chord 18 as indicated at 19. The remainder of the top surface 20 is a shallow conical frustum merging gradually with the bottom of the post 10 which may be formed with a shallow peripheral groove 21 to increase its flexibility.

To enable the golf ball to be supported securely on grass or uneven ground surfaces, the base 11 is made relatively flexible and adapted for engagement with the ground mainly around its periphery. This is accomplished by forming a depending continuous rim or bead 22 around the arcuate and chordal portions of the outermost edge of the base. Because of the relative thinness of the base adjacent its periphery, the base is adapted to flex readily and thus adapt itself automatically to unevenness of the ground surface without appreciable tilting of the ball supporting cup 15.

On the underside, the base is reinforced to withstand the severe bending stresses incident to driving the supported golf ball while still preserving the over-all flexibility of the tee. Herein, this is accomplished by three radial ribs 23 and 24 integral at their outer ends with the bead 22 and joined together at the center of the base, the lower edges of the ribs lying in the same plane as the bottom of the bead. The rib 23 extends perpendicular to the chordal portion of the bead 22 so as to lie parallel to the line of flight of the driven ball and therefore in the plane in which the tee is tipped and bent as an incident to driving the ball. The other two ribs 24 are spaced equidistantly from each other and 35 the points 17 so as to trisect the arcuate portion of the bead 22. The base 11 is thus reinforced effectually to withstand the bending stress involved while at the same time the forward edge portion of the base reinforced by the ribs 24 is adapted to bend readily as required to enable the ball to be driven from the cup 15 without interference by the lip of the cup or any tendency to be deflected from the line of flight determined by the motion of the club head.

The downwardly opening recesses thus formed in the bottom of the base between the ribs 23 and 24 and the bead 22 afford space for receiving grass blades and thus permit the bead 22 to come into contact with a firm ground surface. 50 To obtain such contact on a grass-covered surface, the tee may be twisted back and forth as the base is pressed against the ground, the grass blades thus becoming packed into the bottom recesses. In this operation, the rim 22 of the flexible base adapts itself automatically to the con-

tour of the ground and becomes supported firmly with the post 10 disposed substantially in upright position so as to support the ball properly in spite of the grassy or uneven character of the ground. For the same reason, the ball becomes supported at a uniform height above the ground surface proper irrespective of variations in the height of the grass.

Between the cup 15 and the base 11, the post 10 is of reduced diameter to correspondingly decrease the resistance of the post to bending in releasing the ball from the cup while at the same time providing sufficient strength to enable the cup enlargement to be withdrawn from the mold. Herein, the diameter is smallest substantially midway between the ends of the post and increases progressively in opposite directions to the top of the base and to a narrow cylindrical band 25 around the lip 26 of the cup 15. By thus forming a peripheral groove around the post, the latter may be grasped and held readily between the middle and forefinger of the user's hand while the latter is holding a golf ball seated in the cup. With the tee and ball thus held, pressing of the tee base against the ground in the manner described above and placing the ball on the tee are effected in a single simple operation.

Owing to the ready flexibility of both the post 10 and the base 11 and of the cup lip 26 due to the narrowness of the band 25, the ball supporting cup 15 may be made somewhat larger in diameter than in ordinary rigid golf tees without increasing to any appreciable degree the resistance offered by the tee.

The link 12 is made very flexible and attached to the base 11 so that the link does not in any way interfere with positioning of the tee proper as described above. To these ends, the link is made relatively thin and flat with its underside surface spaced above the plane of the bottom of the base as shown in Fig. 5. In this position, that portion of the link adjacent the bead 22 does not engage the ground surface or prevent full engagement of the bead and the ground. Owing to the ready flexibility of the link, the remaining portion adapts itself to irregularities in the ground adjacent the tee proper without any tendency to tip the latter.

In the use of the tee above described, the base 11 is pressed firmly against the ground surface so as to locate the cup 15 substantially horizontally and thus adapted to hold a ball securely at the desired height above the ground. The link 12 is extended along the ground with the weight 13 disposed on the side of the tee opposite the golf player. The side of the golf ball which is struck by the club head thus overhangs the chordal edge 18 of the base a substantial distance as shown in Fig. 2. As a result, the moving club head engages the ball first even in the case of a relatively low swing. Thus, the ball is always supported properly at the time the blow is struck.

Although holding the ball securely under the widely varying conditions which may be encountered in use, the tee offers substantially less re-

sistance than prior tees to the release of the ball from the cup 15 when the ball is struck by the club. This is due to the combined flexibility of the parts as above described which permits the post 10 to tilt forwardly due to its own yieldability or by bending of the base 11. Substantially the full impact of the club is thus available to propel the ball.

This application is a continuation-in-part of my co-pending application Serial No. 62,108, filed November 26, 1948, now abandoned.

I claim as my invention:

1. A golf tee molded from rubber and comprising a shallow frusto-conical disk-like flexible base, a post upstanding from said base along the axis thereof and terminating in a cup for receiving an ordinary golf ball, the periphery of said base being defined in part by an arc concentric with said axis and in part by a chord spaced from said axis a distance less than the radius of said ball so as to be disposed out of contact with the face of a golf club striking a ball supported on said cup, a bead extending around and depending from said base around the entire periphery thereof, angularly spaced ribs depending from the bottom of said base and radiating from said axis to said bead, one of said ribs being integral with the center of the chordal portion of said bead, a weight adapted to rest upon the ground at a point spaced from said base, and a flexible band connecting the outer peripheries of said base and said weight with the lines of connection disposed above the planes of the bottom surfaces of the base and weight, said band extending substantially parallel to said chord.

2. A golf tee molded from rubber and comprising a shallow frusto-conical disk-like flexible base, a post upstanding from said base along the axis thereof and terminating in a cup for receiving an ordinary golf ball, a bead extending around and depending from said base around the entire periphery thereof, said bead being of greater width than the thickness of the adjacent part of said base, angularly spaced ribs depending from the bottom of said base and radiating from said bead, a weight adapted to rest upon the ground at a point spaced from said base, and a flexible band connecting the outer peripheries of said base and said weight with the lines of connection disposed above the planes of the bottom surfaces of the base and weight.

PAUL J. BARNARD.
